UNITED STATES PATENT OFFICE

164,264

SAW

Robert E. Roberts, San Diego, Calif.

Application April 25, 1950, Serial No. 9,459

Term of patent 14 years

(Cl. D93—3)

To all whom it may concern:

Be it known that I, Robert E. Roberts, a citizen of the United States of America, residing at San Diego, in the county of San Diego and State of California, have invented a new, original, and ornamental Design for a Saw, of which the following is a specification, reference being had to the accompanying drawings, forming a part thereof.

Fig. 1 is a side elevational view of a saw showing my new design, Fig. 2 is a fragmentary side elevational view thereof, and Fig. 3 is a fragmentary top view thereof.

I claim:

The ornamental design for a saw, substantially as shown.

ROBERT E. ROBERTS.
